UNITED STATES PATENT OFFICE.

TALBOT C. DEXTER, OF PEARL RIVER, NEW YORK.

PAPER-CUTTING MACHINE.

No. 923,154.

Specification of Letters Patent.

Patented June 1, 1909.

Application filed July 18, 1908. Serial No. 444,188.

To all whom it may concern:

Be it known that I, TALBOT C. DEXTER, a citizen of the United States, residing at Pearl River, in the county of Rockland and State 5 of New York, have invented certain new and useful Improvements in Paper-Cutting Machines, of which the following is a specification.

My invention relates to improvements in
10 the clamp controlling mechanism of paper
cutting machines of the type set forth in
Patents Nos. 871,572 and 871,573, granted
to me November 19th, 1907, the object of
15 my present invention being to provide a
simple and effective manually operated de-
vice for controlling the hook which connects
the two parts of the clamp, whereby the ma-
chine may be operated continually as a
20 power clamp, or as a manual power clamp, or
the lower part of the clamp left in engage-
ment with the pile after its power operation.

In order that my invention may be fully understood, I will first describe the same with reference to the accompanying drawings and afterward point out the novelty more particularly in the annexed claims.

In said drawings Figure 1 is a front elevation of a paper cutting machine having my improvement applied thereto. Fig. 2 is a side elevation of the same. Fig. 3 is an enlarged detail vertical sectional view showing the improved clamp controlling mechanism, and Fig. 4 is a detail rear elevation of the same.

35 For the purpose of illustrating my invention I have shown it applied to the paper cutting machine set forth in Patent No. 807,730, granted to me December 19th, 1905. It will be understood, however, that I do not
40 intend to limit my invention to its application to this particular form of paper cutting machine, since it can with equal advantages be applied to many other forms of paper cutting machines in which the clamp is made
45 in two parts or members arranged for either power operation or manual operation at the will of the operator.

The side frames or standards 1 are firmly braced and connected by the top rail or cross-head 2, the center rail 3, the bottom rock shaft 4, the cutter operating shaft 16, clamp operating shaft 113 and the main power shaft 22 of the machine.

80 is a paper supporting table or platform. The reciprocating cross-head 7, carrying the cutting blade 8, is mounted to slide ver-

tically and transversely of the machine in the vertical guide slots formed in the side frames or standards 1, said cross-head 7 being suitably anchored to the top rail 2 by means not shown, and connected through links 18 with the cranks 17 mounted upon the knife operating shaft 16.

The paper holding clamp is formed of two parts or members 105 and 106 which are in effect two transversely arranged bars resting one above the other and operating in suitable vertical slots or guide-ways formed on the inner faces of the side frames or standards 1. The upper part of member 105 of the clamp has secured to its opposite ends the depending rack bars 109 which are in constant mesh with gears 112 mounted upon the opposite ends of the clamp operating shaft 113 which is freely journaled in the side frames of the machine. These rack bars 109 rest in vertical slots or guides formed in the opposite ends of the lower part or member 106 of the clamp, so that said lower member can move freely vertically upon the upper portions of rack bars 109.

Attached to the opposite ends of the lower clamping member 106 are the ends of ropes or chains 108 which pass up over the grooved pulleys 110 and are connected at their lower ends beneath the paper support platform with a counterbalance weight W which balances the weight of the clamping members and the attached parts. 85

132 is a centrally arranged foot lever secured to the rock shaft 4 and having formed integral with it a rearwardly projecting rock arm 133 which rests centrally beneath the counterweight W for raising the weight and lowering the member 106 of the clamp independently of the power mechanism. 95

120 is a heavy hook freely pivoted upon a pin 121 mounted in bracket 122 secured to the rear face of the upper clamp member 105. This hook 120 extends vertically and is adapted to engage at its lower hook end with the rearwardly presented flange or upper wall 106^a of the lower clamp member 106 to securely couple the two clamp members 105 and 106 to cause them to operate as one. 105

The upper end of the heavy hook 120 is provided with a rearwardly presented pin or lug 125 which is adapted to engage and move upon the forward face of a plate or bar 130, which is pivoted at 131 in the rearwardly presented bifurcated end of bracket arm 132, secured at 133 to the under face of the top

5 rail or cross-head 2. The upper end of the plate or bar 130 above the pivot 131, is bifurcated as shown at 135 to receive the rear end of a controlling rod 136, to which it is pivoted by pin 137. This controlling rod 136 passes forwardly through the front wall of the top rail 2 in which it is journaled at 138. A block or collar 139 is mounted upon the rod 136 to confine upon said rod between the 10 block and the front wall of the top rail 2 an expansion spring 139^a which tends to move the rod 136 rearwardly in its bearing for placing the controlling plate or bar 130 in the position shown in full lines in Fig. 3.

15 The bearing 138 is extended forwardly from the top rail 2 and has cut into its forward end a spiral cam face 140, with which engages the similar cam face 141 formed on a hub 142 of a hand lever 143. This hand 20 lever 143 is freely journaled upon the rod 136 with its cam face in engagement with the cam face of the bearing, a nut or other suitable device 145 upon the forward end of the rod 136 serving to hold the lever 143 in 25 place.

30 150 is a stop pin projecting from the face of the top rail or cross-head 2 into the path of the hand lever 143, so as to limit the movement of said lever in one direction as indicated particularly in Fig. 1.

35 The knife operating shaft 16 and clamp operating shaft 113 may be driven in any suitable manner from the main power shaft of the machine, such for instance by the mechanism described and illustrated in my above named Patent No. 807,730.

40 The operation of the device will be understood from the following brief explanation: The parts shown in the drawings in full lines are in their normal position in which position the plate or bar 130 is in engagement with the heel or lug 125 of the hook 120 to hold said hook disengaged from the flange or plate 106^a of the lower clamp 106. When 45 the parts are in this position said hook will be held in disengaged position, whether the clamp is raised or lowered. When the parts are in this position, the lower member of the clamp may be manually operated independently of the upper member of the clamp. Furthermore, if both members of the clamp have been moved downwardly by power, and it is desired to retain the lower member in engagement with the pile, the hook 120 55 may be disengaged from the lower member by the operation of the plate or bar 130 to permit the power driven upper member of the clamp to return to its raised position alone. The position shown in dotted lines 60 in Fig. 3 of the drawings, in which the hook 120 is in engagement with the lower member of the clamp, is the position of the parts when the clamp is operated by power. In 65 this position it will be observed that the heel or lug 125 upon the hook is out of en-

gagement with the plate or bar 130. To move the controlling plate or bar 130 from the position shown in full lines to the position shown in dotted lines, the operator rotates the hand lever 143 up into engagement 70 with the stop 150, which action through the cam faces 140 and 141 moves rod 136 forwardly through its bearing compressing spring 139^a, and moves the plate or bar 130 upon its pivot as shown. 75

The operation of the clamp, either by power or manually, is fully explained in my above named Patent No. 807,730, but it will be understood that any suitable form of mechanism may be employed for either the 80 power or manual operation of the clamp without departing from the spirit of my invention, which relates solely to manually controlled means for detachably coupling the two parts of the clamp for conveniently 85 changing from a manual to a power operation and vice versa.

What I claim is:

1. The combination, in a paper cutting machine, of a paper holding clamp comprising two vertically movable parts or members, independent operating means for each of said parts or members, a coupling hook pivotally mounted upon one of said members and movable upon its pivot longitudinally of the machine and adapted to engage a part upon the other of said members, and a manually operated bracket arm movable longitudinally of the machine into and out of engagement with said hook for moving said 100 hook into uncoupled or coupled position. 90

2. The combination, in a paper cutting machine, of the upper and lower clamp bars or members, means for operating said clamping bars or members, a coupling hook pivotally mounted upon one of said members and adapted to engage the other of said members, a bracket mounted upon the machine frame, a plate or bar pivotally mounted upon said bracket and projecting downwardly therefrom adjacent to said hook, and manually operated means for adjusting the position of said plate or bar, substantially as and for the purpose set forth. 105 110

3. The combination, in a paper cutting machine, of the upper and lower clamping bars or members, means for operating said clamping bars or members, a coupling hook pivoted upon one of said members and adapted to engage the other of said members, a 120 bracket arm projecting from the machine frame above said coupling hook, a controlling plate or bar pivotally mounted upon said bracket and projecting downwardly in rear of said hook, a rod pivoted to said controlling 125 plate or bar passing forwardly through the frame, and manually operated means for shifting said rod.

4. The combination, in a paper cutting machine, of the upper and lower clamping 130

- bars or members, means for operating said clamping bars or members, a coupling hook pivoted upon one of said members and adapted to engage the other of said members, a bracket arm projecting from the machine frame above said coupling hook, a controlling plate or bar pivotally mounted upon said bracket and projecting downwardly in rear of said hook, a rod pivoted to said controlling plate or bar passing forwardly through the frame, a spring for moving said rod longitudinally in one direction, and manually operating means for moving said rod in the opposite direction against the action of said spring. 5
5. The combination, in a paper cutting machine, of the upper and lower clamping bars or members, means for operating said clamping bars or members, a coupling hook pivoted upon one of said members and adapted to engage the other of said members, a bracket arm projecting from the machine frame above said coupling hook, a controlling plate or bar pivotally mounted upon said bracket and projecting downwardly in rear 10 of said hook, a rod pivoted to said controlling plate or bar passing forwardly through the frame, a hand lever operatively connected with said rod, and a stop for limiting the movement of said hand lever. 15
6. The combination, in a paper cutting machine, of the upper and lower clamping bars or members, means for operating said clamping bars or members, a coupling hook pivoted upon one of said members and adapted to engage the other of said members, a bracket arm projecting from the machine frame above said coupling hook, a controlling plate or bar pivotally mounted upon said bracket and projecting downwardly in rear 20 of said hook, a rod pivoted to said controlling plate or bar passing forwardly through the frame, a hand lever operatively connected with said rod, and a stop for limiting the movement of said hand lever. 25
